(57) **CLAIM**

The ornamental design for a portable air sander, as shown.

DESCRIPTION

FIG. 1 is a perspective view from the upper front of a portable air sander showing my new design;

FIG. 2 is a perspective view from the upper rear thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof;

FIG. 8 is a bottom plan view thereof;

FIG. 9 is a cross-sectional view, along line 9—9 in FIG. 7, from which the internal structure is omitted; and,

FIG. 10 is a reference drawing showing the portable air sander with a sander disk and an air hose shown in broken lines showing an environmental association for illustrative purposes only and forming no part of the claimed design.
